UNITED STATES PATENT OFFICE.

WELLINGTON W. MUIR, OF LOCKPORT, NEW YORK.

COOLING SYSTEM FOR INTERNAL-COMBUSTION ENGINES.

Application filed August 16, 1922, Serial No. 582,213. Renewed November 12, 1924.

This invention relates to cooling systems for internal combustion engines, and has for its object to provide a system which will enable the manufacturer to locate the water pump at any position desired relative to the radiator and to the water jacket.

With these and other objects in view, the invention consists in the novel details of construction and in the relation of parts 10 more fully hereinafter disclosed and particularly pointed out in the claims.

Referring to the accompanying drawings forming a part of this specification, in which like numerals designate like parts in 15 all the views:

Figure 1 is a diagrammatic view partly in section of a steam cooling system with the pump located on a level near the bottom of the radiator;

Figure 2 is an end elevational view of a portion of the engine casting showing a cover for the rocker arms and their coacting parts;

Figure 3 is a sectional view taken on the line 3—3 of Figure 1;

Figure 4 is a diagrammatic view of a slightly modified form of the system illustrating the pump as located on a level near the top of the radiator;

Figure 5 is a view similar to Figure 4, illustrating a further modified form of the system having its pump located on a level near the middle of the radiator;

Figure 6 is a view similar to Figure 5 illustrating another modification of the system having its pump located on a level below the water jacket and near that of the top of the radiator; and

Figure 7 illustrates a still further modification with a pump located on a level with the bottoms of the radiator and water jacket.

In order that the precise invention may be the more clearly understood, it is said: For practical reasons, well known to manufacturers, it is of great advantage to be able to locate the water pump of a cooling system at any point desired relative to the radiator and to the jacket. On the other hand, it is further well known that it is very desirable in steam cooling systems to use centrifugal forms of water pumps and that centrifugal pumps will not operate satisfactorily unless there is a certain head of water maintained on the suction side of the pump. Therefore, when it comes to locating a cen-

trifugal pump at a point low in the steam cooling system, one is liable to not provide a sufficient head of water under all conditions on the suction side of the pump to 60 operate satisfactorily; and this difficulty increases as the position of the pump is raised relatively to the position of the bottom of the radiator.

In addition to this, it is still further well known that unless the air which is sure to find its way into a centrifugal pump is readily gotten rid of, the pump will fail to function properly. That is to say, if a centrifugal pump could be always filled with 70 water it would not be necessary to supply a constant head of water on the suction side of the pump, but due to the pump operating intermittently in practice, unless there is a constant head of water feeding the suction side 75 of the pump, both when it is running and when it is idle, air is inevitably drawn into the pump around the impeller and is trapped there with the water. This presence of air in the pump causes it to fail in its operation 80 due to the fact that the water in the pipe leading from the force side of the pump offers a sufficient resistance to prevent the air from escaping from the impeller of the pump provided it is there in any great quantity. 85

By this invention, on the other hand, the above objections are overcome as will presently appear. Referring more especially to Figures 1 and 3, 1 indicates any suitable engine having a water jacket with a normal 90 water level, at 2. 3 indicates a pipe leading into the radiator 4, having a tank 5, and 6 indicates a pipe leading from said tank 5 to the point 7, where it is joined by the inclined pipe 8 leading to the inlet, or 95 suction side of the pump 9, provided with the shaft 10 and having joined to its delivery side the pipe 11 leading back to the engine jacket, and provided with the goose neck 12 having the bleeder opening 14, and 100 delivering in said jacket as at 13.

The pump 9 is of the centrifugal double impeller type, having the centrally disposed plate 15, carrying on one side a double set of impeller blades 16, and on its other side 105 a double set of impeller blades 17. The condensed fluid from pipe 8 enters the pump 9 at the point 19 between the sets of blades 16, whereupon centrifugal forces carry said fluid radially outward into the convolute channel 20, and the pressure thus generated 110 causes said fluid to pass into the channel 21,

thence to the point 22 between the impeller blades 17. The latter blades by centrifugal action force the fluid into the convolute channel 23 in all respects similar to channel 20, and out of said channel 23 to the point 24 and into the pipe 11.

During the passage of the fluid around the circuit just described, should there be present a mixture of air and alcohol, which 10 is usually the case, the alcohol will be caught in the condensed water before it reaches the point 7, and the air will separate at said point, and be carried off through the vent pipe 30 to the space 31 in the top of the radiator whence it escapes out of the filling opening 32, through the whistle 33 carried by the filling cap 34. Said space 31 is separated from the condensing portion of the radiator by the diaphragm or partition 35 as shown. 15 20 Should any air be carried past the point 7 into the pipe 8, the inclination of said pipe will cause said air to escape back to the point 7 and out the vent 30, while any air that finds its way into the channels 20, 25 21 and 23, will be carried past the check valve 36 around the circuit to be eliminated at the point 7.

It will now be clear that in the construction just disclosed, there may always be 30 sufficient pressure in the system and therefore in the tank 5 due to the air present or to the pressure of the water vapor or steam in the jacket, to raise the condensed liquid from said tank 5 to the point 7 and to maintain the level of said liquid at such point.

It will further be clear that owing to the inclination of the pipe 8 any air which would be in a quantity sufficient to stop the operation of the pump 9 would readily escape up said pipe 8 to the point 7, and be carried to the atmosphere from the vent 30. Any smaller quantity of air that would be caught in the pump 9 would be forced along with the water, past the valve 36, back into 40 45 the jacket and be returned to the suction side of the pump, where it would be eliminated at the point 7.

It thus results that so long as the pump is operating the air is gradually eliminated 50 from the system and the operation of the centrifugal pump on a steam cooling system gets better and better as time goes on. On the other hand, when the pump stops, the inclination of the pipe 8 keeps the pump 55 full of water and prevents air from entering the same, so that it is always primed for starting again. The check valve 36 effectively prevents pressure in the jacket from forcing the water back into the pump 60 through the pipe 11 and through the pump and pipe 8 into the vent 30, when the engine stops suddenly.

In order that the operator may the better learn the condition of his system, a gage 65 glass 40 is provided as illustrated and in

said glass is a float 41 in order to keep it clean or scoured so to speak, and thus better show the level of the water in the jacket. Spring 42 controlled by the screw cap 43 presses on said glass to give it a cushioned support, and prevent breakage during hard usages of travel. A metal shield 44 which only partially surrounds the glass is provided in order to prevent it from being broken due to impacts of cold air or cold 70 water that may splash against the glass. The upper portion 46 of the motor casing is preferably of the shape shown in Figure 2, to provide a space 50 to accommodate the valve rods 47, the rocker arms 48 and their 80 associated parts, which may all be of a standard construction. A cover 49 covers said space 50 and operating parts and further serves to maintain said parts at a relatively warm temperature, and thus tend to 85 prevent expansions and contractions which are found to give trouble in actual use. The peculiar shape shown in Figure 2 in addition forms a small steam space 51 below the point at which the pipe 3 connects with the 90 motor, which space is found to be very useful when it is desired to operate this system on the semi-wet principle.

That is to say, at present it is found desirable to greatly restrict the amount of 95 steam passing into the radiator. Instead of using steam alone in the radiator under the semi-wet system a mixture of steam and boiling hot water is passed through said radiator and in this case it is found to be of 100 advantage to provide a relatively small steam space 51, as indicated, which insures that a certain small proportion of steam always accompanies the water in the radiator.

Coming now to Figure 4, the construction and principle is substantially the same as in Figure 1, the main difference residing in the fact that the filler cap 52 is so located that liquid cannot rise in the jacket higher 110 than said cap and further that the pump 53 is located on a level substantially equal to that of the top of the water jacket and the top of the radiator. However, the pressure in the system causes condensed fluid from 115 the tank 5 to rise to a point 54 sufficiently high to keep the pump 53 always primed. 55 represents a vent and 56 a pipe on the force side of the pump back to the jacket.

In the form of the system shown in Figure 120 5, the arrangement of parts is similar, to that shown in Figure 4, except the pump 58 is located on a level substantially the same as that of the middle portions of the jacket, and of the radiator. In this case the pressure in the system causes liquid to rise from the tank 5 to the point 60 whence the inclined pipe 61 leads to the pump 58 and keeps it always primed. The return pipe 62 carries the fluid back to the jacket.

In the form of the invention shown in Figure 6, the pump 63 is located below the bottom of the jacket, and substantially on a level with the top of the radiator. The 5 pressure of the air and water vapor in the space 65 causes the water condensed in the tank 5 to be raised through the pipe 66 into the tank 67 whence air escapes from said fluid through the vent 68 and the head of 10 water provided by said tank 67 keeps the pump 63 always primed. Pipe 69 returns water from the pump to the jacket.

In the form of the invention shown in Figure 7, the pump 70 is located at the lower portion or below the jacket the pressure 15 in the system causing the condensed water from the tank 5 to rise through the pipe 71 into the tank 72 which supplies a constant head of water on the suction side of the 20 pump through the connection 73.

Any air which may be passed over with the condensed water escapes through openings 74 in the small compartment 75, provided with the float valve 76, which controls 25 the vent 77.

It will now be clear that in all the forms of the invention there is provided a construction which enables the manufacturer to place a self-primed and intermittently operating 30 centrifugal pump at any point relative to the motor and the radiator which may be desired. It will further be clear that each of these forms permit the entrapped air to readily escape from the pump and that the 35 pump may function either continuously or intermittently without any trouble at all in a steam cooling system.

In the form of pump shown in Figure 1, a double set of impeller blades is employed 40 so that it may operate at a low speed. This is a recognized advantage in this art, and of course, each of the other pumps 53, 58, 63 and 70 may be the same type if desired.

By removing the cap 34, the system may 45 be filled with liquid up to the point 32, whereupon it will function as an ordinary water cooled system and therefore, one can readily change this invention from a steam to a water system.

It is obvious that those skilled in the art 50 may vary the details of construction as well as the arrangement of parts without departing from the spirit of the invention, and therefore, I do not wish to be limited to the 55 above disclosure except as may be required by the claims.

What I claim is:—

1. In a cooling system for internal combustion engines, the combination of an engine 60 provided with a jacket; a radiator; a connection between said radiator and said jacket; a pump; a pipe adapted to convey condensed fluid from said radiator upwardly under the influence of pressure; a second pipe joining said first named pipe

above the bottom of said radiator and joining said pump on its suction side; a vent leading to the atmosphere communicating with said first and second named pipes at their point of juncture and adapted to carry 70 air out of the system; and a valved connection between the force side of said pump and said jacket, substantially as described.

2. In a cooling system for internal combustion engines, the combination of a jacket; 75 a radiator; a centrifugal pump; connections between said jacket and said radiator; connections between the force side of said pump and said jacket; a pipe leading from the bottom of said radiator to the atmosphere; 80 and an inclined passage from the suction side of said pump joining said first named pipe at a point between the bottom of said radiator and its opening to the atmosphere adapted to carry away any air before it 85 becomes entrapped in said pump, substantially as described.

3. In a cooling system for internal combustion engines the combination of a jacket; a radiator; a centrifugal pump; connections 90 between said radiator and said jacket; connections between the force side of said pump and said jacket; a pipe leading upwardly from the bottom of said radiator to the atmosphere and adapted to have the condensed fluid from said radiator forced upwardly therein by the pressure existing in the system; and an inclined pipe joined at its upper end to said first named pipe at a 95 point above the bottom of the radiator and joined at its lower end to the suction side of the pump, substantially as described.

4. In a cooling system for internal combustion engines, the combination of a jacket and a radiator connected together; a centrifugal pump located above the bottom of 100 said radiator connected on its force side with said jacket; a pipe leading upwardly from said radiator to the atmosphere; and connections from the suction side of said pump joining said last named pipe at a point above the bottom of said radiator, substantially as described.

5. The method of causing the jacket fluid in the cooling circuit of an internal combustion engine to flow to a desired point in 115 said circuit which consists in vaporizing said fluid; condensing portions of the vaporized fluid; causing the pressure of other portions of said fluid to force the condensed portions thereof to the said desired point; forcing said condensed fluid back into said jacket; and separating out any air which may be entrained in said condensed portions before 120 said forcing action takes place.

6. The method of causing the jacket fluid in the cooling circuit of an internal combustion engine to flow to any desired point in 125 said circuit which consists in vaporizing said fluid; condensing portions of the vaporized

fluid; causing the pressure of other portions of said fluid to force the condensed portions thereof to the desired point; forcing said fluid back into said jacket; and separating out any air which may be entrained in said condensed portions at said point; before passing said fluid back to said jacket.

7. In a cooling system for internal combustion engines, the combination of a jacket and a radiator connected together; a pump located above the bottom of said radiator connected on its force side with said jacket; a vent passage leading upwardly from said radiator to the atmosphere; and connections from the suction side of said pump joining said last named passage at a point above the bottom of said radiator, substantially as described.

8. In a cooling system for internal combustion engines, the combination of a jacket and a radiator connected together; means for automatically venting said radiator; and means including a centrifugal pump connected on its force side with said jacket, for automatically separating air from liquid in the suction side of said pump and passing it off through its intake passage, while receiving fluid from said radiator.

9. In a cooling system for internal combustion engines, the combination of a jacket and a radiator connected together; a pump connected on its force side with said jacket; and a connection between said pump and radiator including means for automatically

separating air from the liquid present in said pump on its suction side.

10. In a cooling system for internal combustion engines, the combination of a jacket; a radiator; a fluid conducting passage from said jacket to said radiator; a pump, connected on its force side with said jacket, adapted to separate air from liquid in the suction side thereof; and means for conducting said separated air away from said pump while supplying fluid thereto from said radiator.

11. In a cooling system for internal combustion engines, the combination of a jacket; a radiator; a fluid conducting passage from said jacket to said radiator; a pump, connected on its force side with said jacket, adapted to separate air by centrifugal action from liquid in the suction side, thereof; and common means for conducting said separated air away from said pump while supplying fluid thereto from said radiator.

12. In a cooling system involving forced circulation and including a jacket, a radiator, and connections therebetween, the combination of means for separating air from liquid in the suction side of the forcing means; and means for conducting the separated air from said forcing means while supplying fluid thereto from the radiator.

In testimony whereof I affix my signature.

WELLINGTON W. MUIR
